UNITED STATES PATENT OFFICE.

ERNST GRAETZ, OF NEUSELLERHAUSEN, AND E. FERD. REINHOLD, OF NEUSTADT, NEAR LEIPSIC, SAXONY, GERMANY.

TRUCK.

SPECIFICATION forming part of Letters Patent No. 377,486, dated February 7, 1888.

Application filed May 4, 1887. Serial No. 237,051. (No model.)

To all whom it may concern:

Be it known that we, ERNST GRAETZ, of Neusellerhausen, and E. FERDINAND REINHOLD, of Neustadt, near Leipsic, Saxony, in the Empire of Germany, have invented a new and Improved Truck for Furniture, &c., of which the following is a specification.

Our invention relates to the construction of the platform of a truck capable of being raised or lowered, so that when lowered the article can be easily placed upon the same, and when raised transported from place to place.

The invention consists of the various improvements hereinafter set forth.

15 In the accompanying drawings, Figure 1 is a front view of our improved truck. Fig. 2 is a cross-section at line S S, Fig. 1, showing the working-lever folded together. Fig. 3 is a bottom view of one side of the truck. Fig. 20 4 is a side view of the truck, showing the platform raised. Fig. 5 is a side view with the platform lowered and the working-lever extended ready for operation. Fig. 6 is a front view; Fig. 7, a bottom view; Fig. 8, a side 25 view, and Fig. 9 an end view showing a modification.

Frames A A, connected through rods A', are supported on rollers a a, turning on centers F, attached to the outer end of these frames, 30 or on rollers a' a', turning on bolts b, as shown in dotted lines in Figs. 1, 2, and 3. Upon the centers F of these frames levers d are placed, the other ends of which are hinged to the under side of a platform, B. The levers d at 35 the forward frames A are connected with the working-levers D D'. These levers are made in two parts, hinged together at D', to enable the same to be turned over, as shown in Fig. 2. A bolt, e, secures the two parts D D' of these levers when in a straight position, as shown in 40 Fig. 5. The outer ends of these levers are connected together by a cross-bar, E, to act as a handle for moving the truck. At the lower

ends of the levers D a catch-bolt, f, is arranged, connected to a rod, h, capable to work the 45 same near the cross-bar E. This catch-bolt f is made to enter a hole in the center bolts, F, (see i, Fig. 4,) to prevent the levers d d' from moving after the platform has been raised.

The operation is as follows: The levers D' 50 are turned so as to form a straight lever with the part D, and secured in that position through bolt e. The truck is then moved under the piece of furniture to be moved and the levers D D' turned downward, whereby 55 the platform B, together with the article, is raised, capable of being easily moved about.

During the operation of raising the platform B, as above described, the furniture will at the same time be moved away from the wall 60 some distance. Instead of arranging the truck as above described, levers L K may be hinged to the frames A, as shown in Figs. 6 to 9, connected together at their inner ends, n, and supporting at their outer ends, m, the platform B. 65

The bent part of the ends of the levers D are connected through rods G with angle-pieces H, the free ends of which form cams l, operating the levers K. The platform B is guided through bolts p, and receives by this arrangement only an upright movement. 70

What we claim is—

The combination of a truck with movable platform B, levers d, sectional working-levers D D', hinged at D', and with bolt e, cross-bar 75 E, catch-bolt f, and connecting-wire h, as and for the purpose described.

In testimony whereof we have signed our names to this specification in the presence of two subscribing witnesses.

ERNST GRAETZ.
E. FERD. REINHOLD.
